INVENTOR,

By *Henry B. Stauffer*

ATTORNEY.

UNITED STATES PATENT OFFICE

2,545,678

PRY TYPE CAP REMOVER

Charles C. Stauffer, Durham, N. C.

Application December 12, 1947, Serial No. 791,425

2 Claims. (Cl. 81—3.46)

1

This invention is in openers for cans, jars, and the like and more particularly for vacuum-sealed glass jars.

Notwithstanding many different types of food are packaged and sold in hermetically sealed jars, no satisfactory means for opening such jars has as yet been devised. In many cases, the packers recommend that the cap be pried off with the back of a knife blade or similar flat implement. In practice, it is customary to use an ordinary can opener, which invariably deforms the cap. In other cases, resort is had to puncturing the cap to break the vacuum seal before the lid is removed. In either case, it is impossible to reclose the container in anything approaching an airtight manner.

The principal object of my invention is to provide a simple tool especially suited for the opening of vacuum-sealed jars and other containers having removable tops.

Another object is to provide a tool for opening containers of the nature described without deforming the caps, the same being usable in reclosing the container.

Other objects will be apparent from a reading of the following specification and claims.

In the drawings:

Figure 1 shows a simple form of the opener of my invention; and

Figure 2 shows the invention applied to a conventional can and bottle opener.

Referring to the drawings and especially to Figure 1, the opener can be seen to comprise an opener proper 10 and two handles 11 and 12, the members being constructed of any desired sturdy and durable material, preferably steel, and preferably of approximately $\frac{1}{8}$ inch in thickness. Member 10 is flattened, and its extremity 15 is in the nature of a recessed arc.

It will be understood that the opener of my invention is especially adapted for opening that type of container which includes a protruding annular shoulder near the top thereof and a cap having a flat top and a skirt portion which is spaced from but adjacent the said shoulder when the cap is in place.

It is important that the radius of part 15 be such that the operating points 17 and 18 of member 10 be enabled to fit against the container beneath the lid thereof. The radius should, in other words, be somewhat smaller than the radius of the neck of the average container to be opened.

In operation, the device is held in the hand of the user; operating points 17 and 18 (and usually the edge of recess 15) are inserted beneath

2

the lid of the container and the device twisted by simultaneous downward pressure upon arm 11 and upward pressure upon arm 12, or vice versa. The container caps will be easily removed without noticeable distortion.

Figure 2 illustrates the manner in which the invention may be applied to an opening implement of known design which includes a puncturing element 20 at one end thereof and a bottle opener 21 at the other end thereof. No additional stock is required. Such a can opener may be stamped out of the usual blank with the opener of this invention as an integral part thereof. To this end, the opener proper 25, shaped as 15 before explained, is recessed in the edge of the implement of Figure 2 by curving inwardly the edge portions 26 and 27 adjacent thereto, the radius of the curves 26 and 27 being larger than the radius of the average container to be opened 20 so as not to interfere with the operation of points 30 and 31 of member 25.

The foregoing description is in specific terms, and many modifications will suggest themselves so that for the true scope of the invention reference should be had to the appended claims.

I claim:

1. In an implement adapted to remove the cap from a sealed container having a shoulder near the top thereof and a cap having a skirt portion spaced from but adjacent said shoulder, a member having two spaced relatively straight edge portions on one edge thereof, two spaced operating points for said edge, and a web between said points of recessed arcuate formation the radius 30 of the arc of said formation being smaller than the radius of the neck portion of the average container to be opened, and two additional recessed arcuate portions connecting said web with said straight portions so as substantially to align 35 said operating points therewith, the radius of curvature of the said additional arcuate portions being larger than the capped portion of the average container to be opened.

2. In an implement adapted to remove the cap from a sealed container having a shoulder near the top thereof and a cap having a skirt portion spaced from but adjacent said shoulder, a member having two spaced relatively straight edge portions on one side thereof, two spaced operating points for said edge and a supporting web 45 joining said points said web having a recessed extremity for substantially preventing contact between said extremity and the container when the implement is in operating position, and two additional recessed portions connecting said web

with said straight edge portons so as substantially to align said operating points therewith and substantially to prevent contact between a container and said additional recessed and said straight edge portions of said member when the 5 implement is in operating position.

CHARLES C. STAUFFER.
